Fig. 5.

To all whom it may concern:

Be it known that I, Erdick Nelson, a citizen of the United States, residing in the city of Naperville, county of Cook, and State of Illinois, have invented a new, original, and ornamental Design for a Combined Knife Sharpener and Buffer, of which the following is a specification, reference being had to the accompanying drawings forming a part thereof.

Fig. 1 is a top plan view of a combined knife sharpener and buffer, showing my new design;

Fig. 2 is an end elevational view thereof;

Fig. 3 is a side elevational view thereof;

Fig. 4 is an elevational view of the other end thereof;

Fig. 5 is a partial section taken upon the line 5-5 of Fig. 4;

Fig. 6 is a rear elevational view thereof; and Fig. 7 is a sectional view taken upon the line 7-7 of Fig. 6.

The transparent hood is movable, being shown in one position over the buffer in Figs. 1 and 3 and in its alternate position over the knife sharpener in Fig. 6.

I claim:

The ornamental design for a combined knife sharpener and buffer, as shown.
